UNITED STATES PATENT OFFICE.

CHARLES E. BAKER AND ARTHUR W. BURWELL, OF CLEVELAND, OHIO.

PROCESS OF PRODUCING SODIUM PEROXID.

SPECIFICATION forming part of Letters Patent No. 739,375, dated September 22, 1903.

Application filed December 12, 1902. Serial No. 134,983. (No specimens.)

To all whom it may concern:

Be it known that we, CHARLES E. BAKER and ARTHUR W. BURWELL, citizens of the United States, residing at Cleveland, in the county of Cuyahoga and State of Ohio, have invented certain new and useful Improvements in Processes of Producing Sodium Peroxid, of which the following is a specification.

This process is intended for the rapid and complete conversion of sodium into its peroxid.

The process is distinguished from those heretofore proposed or in commercial use by the fact that the metallic sodium is maintained in a fluid—that is, a liquid or gaseous—condition and by the thorough admixture of the fluid sodium and oxidizing agent, which is usually air.

The generic process may be carried out in two specifically different ways, as follows:

First. The sodium is melted and a stream or streams of air are blown through it from a pipe or finely-perforated nozzle. Instead of air, oxygen, steam, or other gaseous or solid oxidizing agent may be injected or distributed through the body of molten sodium.

Second. The sodium is heated to a temperature sufficient to vaporize it, and the sodium vapor is thoroughly intermingled with air or other oxidizing agent. The sodium is thus oxidized with great rapidity and its peroxid precipitates to the bottom of the chamber in which the reaction is effected.

It will be seen that this process is a much quicker and more economical one than that in common use, in which lumps of solid sodium are heated and a current of air is passed in contact with their surface only.

In practicing our process an excess of oxidizing agent is necessarily employed, since otherwise the whole of the sodium will not be converted to peroxid. The air or other oxidizing agent is preferably carefully dried before being brought into the presence of the sodium.

We claim—

1. The process of producing sodium peroxid, which consists in bringing sodium into a fluid condition and intermingling an oxidizing agent therewith in excess, as set forth. 50

2. The process of producing sodium peroxid, which consists in bringing sodium into a fluid condition and intermingling a gaseous oxidizing agent therewith in excess, as set forth. 55

3. The process of producing sodium peroxid, which consists in bringing sodium into a fluid condition and intermingling air therewith in excess, as set forth.

In testimony whereof we affix our signatures in presence of two witnesses.

CHARLES E. BAKER.

ARTHUR W. BURWELL.
